US00D917433S

(12) **United States Design Patent** (10) **Patent No.:** **US D917,433 S**
(45) **Date of Patent:** **** Apr. 27, 2021**

(54) **MICROPHONE**

(71) Applicant: **ZHAOQING JUNFENG ELECTRONICS CO LTD**, Guangdong (CN)

(72) Inventor: **Wanxuan Wang**, Guangdong (CN)

(73) Assignee: **ZHAOQING JUNFENG ELECTRONICS CO LTD**, Guangdong (CN)

(**) Term: **15 Years**

(21) Appl. No.: **29/751,266**

(22) Filed: **Sep. 19, 2020**

(51) **LOC (13) Cl.** **14-01**

(52) **U.S. Cl.**

USPC **D14/228**

(58) **Field of Classification Search**

USPC D14/228, 225, 226, 229, 227; D13/108, D13/110; 181/158; 381/174, 355, 362; D21/483

CPC H04R 25/00; H04R 19/04; H04R 11/04; H04R 1/08

See application file for complete search history.

(57) **CLAIM**

The ornamental design for a microphone, as shown and described.

DESCRIPTION

FIG. 1 is a top perspective view of a microphone, showing my design.

FIG. 2 is a bottom perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof; and,

FIG. 8 is a bottom plan view thereof.

The broken lines in the drawings depict environmental structure and boundaries and form no part of the claimed design.

1 Claim, 8 Drawing Sheets
